UNITED STATES PATENT OFFICE.

HENRY F. STARRETT, OF CHICAGO, ILLINOIS, ASSIGNOR TO STARRETT MANUFACTURING COMPANY, OF CHICAGO, ILLINOIS, A CORPORATION OF ILLINOIS

PANEL-BOARD.

1,321,486.

Specification of Letters Patent. Patented Nov. 11, 1919.

Application filed October 27, 1916. Serial No. 128,133.

To all whom it may concern:

Be it known that I, HENRY F. STARRETT, a citizen of the United States, residing at Chicago, in the county of Cook and State 5 of Illinois, have invented new and useful Improvements in Panel-Boards, of which the following is a full, clear, concise, and exact description, reference being had to the accompanying drawing, forming a part 10 of this specification.

My invention relates to improvements in panel boards; and particularly to panel boards for use in connection with electric lighting and power circuits.

One of the objects of my invention is to provide a panel board constructed from a plurality of units, whereby large-sized panel boards may be formed, using in the construction standard units, which units may 20 be removed from place after assemblage for the purpose of change, repair, etc., without disturbing the electrical connections of the remaining units of the board and without disturbing or displacing the 25 bus-bars. Further objects of the invention will appear more fully in the accompanying specification and drawings.

For the purpose of disclosing my invention, I have illustrated in the accompanying 30 drawings one embodiment thereof. In said drawings

Figure 1 is a plan view of a panel board embodying my invention;

Fig. 2 is a sectional view taken on the 35 line 2—2 of Fig. 1 looking in the direction of the arrows;

Fig. 3 is a perspective view of the assembly frame of my board, together with an insulating frame mounted thereon;

Fig. 4 is a fragmentary enlarged sectional view taken on the line 2—2 of Fig. 1 showing the method employed for supporting the main bus-bars;

Fig. 5 is a section on the line 5—5 of Fig. 4 illustrating in detail the main bus-bar 45 supporting means; and

Fig. 6 is a rear view of the cover-plate on which the sockets are mounted, and illustrates the recesses or channels therein which 50 accommodate the main bus-bars.

In the embodiment illustrated in the accompanying drawings, I provide an assembly frame 1, formed of the two top and bottom members 2, the two side members 3 55 and the two intermediate members 4. These

members preferably are formed of channel iron and are all bolted or riveted together to form a rectangular assembling and supporting frame 1 for the board.

The board is formed of a plurality of 60 sections or units 5. In the embodiment illustrated, each unit comprises a base 5^a of insulating material having formed in the front face thereof a central or longitudinally extending channel 5^b, as clearly illustrated in the detailed section of the lower left-hand unit of Fig. 1. Fitting within this channel is a cover plate 6, also formed of insulating material, which when placed in position has its top flush with the top 70 of the base 5^a. Formed on the rear face of the cover plate are suitable recesses or channels 6^a for the sub-bus-bars 7, which sub-bus-bars have suitable cross extensions 7^a to make proper electrical connections. 75 The cross extensions are insulated from the main bus-bars by suitable insulating plates, such as 7^b, laid in recesses or channels, such as 7^c, which are wider and not as deep as the recesses 6^a. (See Fig. 6). The recesses 80 7^c are of such a depth that when the insulators 7^b are laid therein and interposed between the cross extensions and the main bus-bars, the exterior surface of the main bus-bars will lie in substantially the same plane 85 as the back surface of the cover-plate 6. The front face of the plate 6 is provided with suitable openings and the sub-bus-bars and the cross-connectors 90 have tapped therein suitable holes 8 registering with the openings in the cover plate to receive the securing screws of the fuse receptacles 9 mounted on the front face of the unit as clearly illustrated and described in my Patent No. 1294185 issued Feb. 11, 95 1919 and entitled Panel board and panel board construction. In addition to the fuse receptacles there are also provided suitable switches 10, which switches are interposed between the fuse receptacles and the branch 100 wire terminals 11. The sub-bus-bars 7 at one end are turned up through openings 11^a in the cover plate and are constructed to form terminals, as at 12, lying on the front face of the unit.

The units in the embodiment illustrated are placed against and in front of the side and intermediate members of the frame, resting thereon and are spaced apart by means of spacer bars 13, which spacer bars 110

are provided at regular intervals with branch wire notches 14, to permit the ends of the branch wires to be led up through the spacers and connected with the branch wire terminals 11 on the units. The ends or terminals 12 of the sub-bus-bars are connected by removable connections in the form of screws 15 with bus-bar connectors 16, which connectors extend from the bus-bars 17 mounted on the assembly frame. In the present instance, the board is a three-wire board, and there are, therefore, provided, of course, three bus-bars. These bus-bars are mounted one above the other and are secured in position to the frame at the upper and lower end of the panel by means of a bolt 18. This bolt is surrounded by an insulating tube 19 (see Figs. 4 and 5). Between the top member 2 of the frame and the bottom bus-bar there is inserted an insulating spacer tube 20 which acts as an insulating support for this bus-bar. Between the bottom bus-bar and the next succeeding bus-bar a similar but shorter insulating tube spacer 21 is inserted which serves as a support for this bus-bar. The top bus-bar and the middle bus-bar are likewise separated by an insulating tube spacer 21 and the nut 22 on the top of the bolt is suitably insulated by an insulating washer 22* from the top bus-bar. The upper end of the bolt 18 is threaded to receive the nut 22*, the bolt and nut serving to hold the bus-bars and intermediate insulating spacers in position. The lower ends of the bus-bars are supported in substantially the same manner. The bolt 18 for supporting the bus-bar in this case is mounted upon a cross piece 23, which may be made, if desired, of insulating material, screwed or otherwise secured to the intermediate members 4. It is thus seen that the bus-bars are mounted on the assembly frame wholly independent of the panel-board units.

In the structure illustrated, there are provided two sets of units of three units each; these sets being arranged side by side, and surrounding each set of units is an insulating frame formed of the side members 24 and the top and bottom members 25. These members are secured together and to the frame by means of corner irons 26. Each corner iron is provided at its bottom with a laterally extending flange 27 by which it is bolted to the frame, and on each of its sides is provided with a longitudinally extending slot 28. The ends of the members are provided with bolts 29 extending therethrough, which bolts fit in the slots 28 and at their ends receive wing nuts 30. Due to the fact that the corner irons are longitudinally slotted, the insulating sides of the frame may be adjusted vertically for various purposes, and at the same time they are held securely in position by means of the wing

nuts 30. The side members of the insulating frame are provided with suitable notches 31 for the accommodation of the bus-bar connectors. These connectors 16, as will be noted, are preferably U-shaped, as shown in Figs. 2 and 4, and, as heretofore explained, are removably connected to the terminals of the units by means of the screws 15. The frames surrounding each set of units form between them a bus-bar gutter, and when the assembled board is placed in the cabinet 32 the units, as will be noted in Figs. 2 and 4, are sufficiently spaced apart from the bottom of the cabinet to form a suitable wiring pocket 33 between the bottom of the cabinet and the bottom of the units to accommodate the various branch or consumption circuit wires. Likewise between the sides and tops of the cabinets and the insulating frame are formed wiring gutters 34 for the accommodation of branch or consumption circuit wires.

By the above construction it will be noted that the units of the panel board are only held in position by their snugness of fit in the frames and by their connections with the bus-bars. It will also be noted that in event it is desired to remove any one of the units for the purpose of substitution, repair, etc., it is merely necessary to disconnect the branch circuit wire connections for that particular unit, and also to disconnect the unit from the bus-bar connections by removing the screws 15, thereby absolutely freeing the unit so that it may be lifted out of position without trouble, without disturbing the electrical connections of the remaining units and without displacing or disturbing the electrical connections of the bus-bars.

It will also be noted that in making a removal of this character, the disconnecting of the terminals of the sub-bus-bars of the unit from the bus-bar connections, by removing the screws 15, renders that particular section dead, so that the disconnection of the branch wires may be proceeded with without danger to the operator.

It will also be noted that each unit of the panel-board in itself comprises a sub-panel-board formed of a base, a cover, a plurality of sub-branch bars held in position between the base and cover, with suitable electrical equipment mounted on the front face of the sub-panel-board.

While I have shown, illustrated and described one embodiment of my invention, it will be understood that various changes and modifications may be made therein without departing from the spirit of the invention as set forth in the appended claims.

In the structure illustrated, I have shown one unit space as being left blank, to illustrate not only that the board may be made up of an odd number of units but that, if

95

desired, a different form of unit may be used in this space. Obviously, any type of circuit-controlling apparatus could be used on the standard supporting units assembled to 5 form the built-up panel-board, and my invention is not limited to the specific embodiment thereof herein illustrated and described, but is capable of many variations and applications without departing from 10 its spirit and scope as set forth in the appended claims.

My copending application Serial No. 168,019, so far as concerns common subject-matter, is a continuation and division of this 5 application, and the generic claims have been included in my co-pending application Serial No. 168,019.

Having thus described my invention, what I claim as new and desire to secure 10 by Letters Patent, is:

1. The combination with a cabinet, of a panel board mounted therein comprising an assembly frame, a plurality of panel board sections, a plurality of panel board 25 units in each section carrying suitable electric equipment mounted upon said frame and spaced apart by said frame from the bottom of the cabinet whereby a wiring pocket is formed between said sections and 30 the bottom of the cabinet, connecting terminals associated with each of said units, insulating frames surrounding and inclosing a plurality of said units, whereby a bus-bar gutter is formed between said frames, bus-bars mounted on said assembly frame, and 35 within said gutter, and means for connecting the terminals of said sections with the bus-bars which means permits the removal of each unit without disturbing the connections to the other units and without displacing the bus-bars.

2. A panel board comprising an assembly frame, a plurality of bus-bars mounted on said frame, a plurality of panel board units 45 each carrying electrical equipment for a plurality of circuits mounted on said frame, connecting terminals carried by each unit common to the equipment carried on each of said units, means to connect said terminals to the bus-bars, said means permitting the disconnection and removal of the units without affecting the connections of the other units and without displacing the bus-bars.

3. The combination with a cabinet, of a plurality of bus-bars stationarily mounted therein, a plurality of panel board units carrying circuit controlling apparatus for a plurality of circuits mounted in said cabinet, connecting terminals carried by each of said units common to the circuit controlling apparatus carried by each of said units, said bus-bars being supported independently of said units, and means connecting the terminals of the units with the bus-

bars which permit the removal and disconnection of each unit without affecting the connection of the other units and without displacing the bus-bars.

4. In a panel-board, the combination with 70 an assembly frame, an insulating frame comprising insulating members mounted on the assembly frame and extending at right angles thereto, a plurality of panel-board units, each unit comprising a base carrying 75 a plurality of bus-bars and electrical equipment connected with said bus-bars, the said units being mounted on said frame, spacer members formed of insulating material interposed between the units notched to form 80 branch circuit wire openings, a plurality of bus-bars mounted on the assembly frame, and means for connecting the bus-bars on the units with the bus-bars on the frame, said means permitting the removal of each 85 unit without disconnecting the remaining units and without displacing the bus-bars.

5. In a panel-board, a support, bus-bars mounted thereon, a plurality of panel units mounted on said support, electrical equipment for a plurality of circuits carried by 90 each of said units, said units being individually removable independently of the bus-bars, and separable electrical terminal connections common to the equipment of each 95 unit interconnecting each panel unit and the bus-bars.

6. In a panel board, the combination with 100 an assembly frame, of a pair of insulating frames mounted upon said assembly frame, a bus-bar gutter formed between said frames, a plurality of panel-board units carrying electrical equipment mounted on said assembly frame and within said insulating frames, terminal connectors carried by each 105 unit, a plurality of bus-bars mounted on said assembly frame in said bus-bar gutter, and means for connecting the terminals of each unit to the bus-bars, said means permitting the removal of each unit independently 110 of the other units without disturbing the connections of the other units and without displacing the bus-bars.

7. In a panel-board, a support, a plurality of series of individually-removable panel 115 units mounted on said support, electrical equipment for a plurality of circuits carried by each of said units, bus-bars mounted on the support, and separable electrical terminal connections common to the equipment of each unit interconnecting each panel unit and the said bus-bars.

8. In a panel-board, a support, a plurality of series of electrically-equipped individually-removable panel units carrying circuits controlling apparatus for a plurality 125 of circuits mounted on said support, bus-bars mounted on the support and common to all the units, and separable electrical terminal connections common to the circuit 131

- controlling apparatus of each unit inter-connecting each panel unit and the said bus-bars.
9. In a panel-board, a support, a plurality of series of electrically-equipped individually-removable panel units mounted on said support, an insulating barrier for each series of units mounted on said support, bus-bars common to all the units of each pair of series of units mounted on said support, said bus-bars being positioned between each pair of series of units, and separable connections between the electrical equipment on each said units and the said bus-bars.
10. In a panel board, a support, a plurality of series of individually-removable panel units mounted on said support, electrical equipment carried by each of said units, an insulating frame inclosing each series of units, a bus-bar gutter formed by adjacent walls of said frames, bus-bars common to said units positioned in said gutter, and separable electrical connections between each panel unit and said common bus-bars.
11. In a panel board, a support, a plurality of electrically-equipped individually-removable panel units mounted on said support, panel board sections each comprising one or more of said panel units, an insulating frame inclosing each section, a bus-bar gutter formed by adjacent walls of said frames, bus-bars common to all the units and positioned in said gutter, and separable electrical connections between each panel unit and the said bus-bars.
12. In a panel board, a support, a plurality of series of electrically-equipped individually-removable panel units mounted on said support, an insulating barrier for each
- series of units mounted on the support, bus-bars common to all the units of each pair of series of units, said bus-bars being positioned between each pair of series of units, and separable connections between the electrical equipment on each of said units and the said bus-bars.
13. A panel board comprising an assembly frame, a plurality of units carrying electrical equipment mounted on said frame, panel board sections each comprising one or more of said panel units, an insulating frame inclosing each section, a bus-bar gutter formed by adjacent walls of said frames, bus-bars common to said units positioned in said gutter, connecting terminals carried by each unit, means to connect said terminals to the bus-bars, said means permitting the disconnection and removal of a unit without disturbing the connection of the other units and without displacing the bus-bars.
14. The combination with a cabinet, of a plurality of panel board units mounted in said cabinet, panel board sections each comprising one or more of said panel units, an insulating frame inclosing each section, a bus-bar gutter formed by adjacent walls of said frames, bus-bars common to said plurality of units positioned in said gutter, connecting terminals carried by said units, and means connecting the terminals of the units with the bus-bars which permit removal and disconnection of a unit without disturbing the connection of the other units and without displacing the bus-bars.
- In witness whereof I have hereunto subscribed my name.

HENRY F. STARRETT.
